UNITED STATES PATENT OFFICE.

MARTIN C. SCHWAB, OF BALTIMORE, MARYLAND, ASSIGNOR TO GRAVITY CONVEYOR COMPANY, A CORPORATION OF NEW YORK.

COMBINATION DOOR FOR CONVEYERS.

No. 852,460.

Specification of Letters Patent.

Patented May 7, 1907.

Application filed January 11, 1906. Serial No. 295,583.

To all whom it may concern:

Be it known that I, MARTIN C. SCHWAB, a citizen of the United States, residing at Baltimore, in the State of Maryland, have invented 5 a new and useful Improvement in Combination-Doors for Conveyers, of which the following is a specification.

My invention relates to gravity conveyers, particularly of the spiral type, and one of its 10 objects is the provision of simple and efficient means for permitting the insertion of articles into the conveyer without being interfered with by descending articles in the conveyer from a higher elevation.

More particularly it is the object of the present invention to provide for a gravity conveyer an inwardly swinging door which will prevent descending articles from interfering with the convenient insertion of articles into the conveyer at a lower elevation.

Another object of my invention is to provide for a gravity conveyer an inwardly swinging door in combination with an additional door on the outside of the conveyer.

Other objects of the present invention will appear hereinafter, the novel combination of elements being pointed out in the claims.

In the accompanying drawings, Figure 1 represents an elevational sectional view of a 30 spiral gravity conveyer with my invention applied thereto; Fig. 2 is a side view of the conveyer and doors; Fig. 3 is a horizontal section of Fig. 2 taken on the line *a—a* when the sliding door *B* is in its lowermost or closed 35 position; and Fig. 4 is a detailed view illustrating the inwardly swinging door.

In the accompanying drawings, 10 designates a tubular shell which in this instance is shown cylindrical, and provided with an inner core or post 13 which is preferably placed 40 in the center of the shell as shown in Fig. 3. Interposed between the outer shell 10 and the inner post or tube 13 is a spiral plate 12. This spiral plate when secured in position appears 45 to be twisted in the form of an Archimedian screw or in the form of a helix. The spiral may be supported by the inner post or column 13 or by the shell 10, or by both, and the pitch of the spiral may be varied as desired. In fact any form of conveyer may be used, that here shown being merely by way of illustration.

Only a sectional part of the conveyer is shown in this instance, and as passing

through the floors 20 and 30, but obviously 55 said conveyer may be extended throughout any desired length or elevation, and is particularly adapted to be placed in department stores for conveying articles from an upper to a lower landing, or in office buildings to 60 convey articles, for example, mail matter, from any upper landing to a mail box in the basement or any lower landing.

It will be noticed that I have illustrated two doors, one an inside door *A* which is 65 curved to the contour of the shell or tube 10 so that when the door is closed an unobstructed even surface will be presented to the descending sliding packages or articles.

Although the door *A* is herein shown inclined or in the form of a parallelogram to conform substantially to the slant of the spiral 12 opposite the door, the door may be rectangular, or have any other desired and convenient shape. In this instance I have 70 shown an inwardly swinging door *A* as hinged at 2, 2 to the outer shell 10, and when opened inwardly, as indicated in Fig. 3 in dotted lines at *A'*, the door will rest against the central column or core 13 so as to constitute a 75 stop or shield for preventing descending articles from rushing through the opening in the conveyer when the door *B* is open.

It will be seen that the door *A* should be so constructed as to be in engagement with the 80 spiral 12 through the greater part of its lower edge, so as to prevent small articles descending from above the opening from going under the door. This is accomplished by cutting the door *A* to the slant or incline of the conveyer so as to conform to the spiral in a 85 downwardly direction.

The hinges 2, 2 may be each provided with means for automatically closing the door *A* when articles are not being inserted in the 90 conveyer through the opening closed by said door. This is not absolutely necessary however, as descending articles will easily move said door *A* to closed position when said door is free to move. As shown in Figs. 1 and 2, the door *A* when closed engages the depending plate 5 which is fastened to the shell 10 just above the opening in the conveyer and acts as a stop for the door. This stop is so arranged that when the door is closed, either 95 by the springs at the hinges 2, 2 or by means of the descending articles which are thrown by centrifugal force against the door, the in- 100 105

ner surface of the door is preferably flush with the inner surface of the shell 10 so as to not interfere in any way with the free passage of the articles in their downward movement.

5 At the outer side of the door A is situated a normally open fire door B, which is arranged in suitable guides C, C and is held in its normal or open position by the weight D 10 connected thereto through the intermediary of a cable E and a fusible joint F. When a predetermined temperature is reached, the fusible joint F disintegrates or melts and allows the fire door to drop and thereby prevents the possibility of the fire entering the shell 10.

20 The fire door B in this instance moves vertically in grooves G, G of the guides C, C and at a short distance from the shell which distance may be determined by the angle plate 4 secured to the outside of the shell 10, just above the stop plate 5. The downward movement of the door B may be limited by the inclined shelf 3.

25 The door B is preferably of the same shape as the door A, but of larger dimensions, so that in any event any opening into the conveyer will be entirely closed by the door B on the one hand and the guides C, C, guide 30 plate 4, and shelf 3, on the other hand. I have shown in this instance a sliding door, but other doors automatically released in case of fire may be used if desired. For instance, the fire door B could be hinged and held in its open position by the cable or rope 35 E containing a fusible joint F. This construction is illustrated in my co-pending application for patent, Serial Number 269,572, filed November 2nd, 1904, and renewed July 40 13th, 1905.

45 In Fig. 2 the cable E is fastened to the door B at 6 and passes upwardly over the pulley P and thence downwardly to the weight D which normally maintains the door in an open position so that access may be had 50 into the conveyer through the opening therein, which is preferably normally closed by the inwardly swinging door A. The pulley P may be pivoted on the bracket 1 secured to the shell 10.

55 Although I have herein shown one form of my invention, I desire it to be understood that I do not wish to be limited to the precise construction disclosed, as various modifications in the details and arrangement of parts may be made by those skilled in the art and still fall within the principles of my invention.

60 Having thus described my invention, what I desire to have protected by Letters Patents of the United States, is:

1. In a conveyer, the combination of a single door for an opening in said conveyer, and an additional door for said opening.

2. In a conveyer, the combination of a single inwardly movable door for an opening in

the conveyer, and a door on the outside of the conveyer for said opening.

3. In a conveyer, the combination of a single inwardly swinging door for an opening in the conveyer, and an additional door for said opening.

4. In a conveyer, the combination with a normally closed door for an opening in the conveyer, of an additional door for said opening normally in open position, and means for automatically releasing said additional door to closed position.

5. In a conveyer, the combination with an inwardly swinging door for an opening in the conveyer, of an additional door on the outside of the conveyer and for said opening, and means for normally holding said additional door in open position, said means comprising a fusible joint or section for permitting the automatic closing of said additional door when said joint is fused.

6. In a conveyer, the combination with an outer shell and an inner core, of an interposed spiral blade, a single door for an opening in the outer shell above the spiral blade, and an additional normally open door for said opening.

7. In a conveyer, the combination with an outer shell and an inner core, of an interposed spiral blade, an inwardly swinging door for an opening in the conveyer at or near the landing, an additional door on the outside of the conveyer, and means for holding said additional door normally in open position, said means comprising a fusible joint or section to effect the automatic release of said additional door when said section is closed.

8. In a spiral gravity conveyer, the combination with an outer shell and an inner core, of an interposed spiral blade, an inwardly swinging door above the spiral and conforming substantially to the inclination thereof, a fire door on the outside of the conveyer, and means for normally holding said fire door in open position, said means comprising a fusible connection to permit the fire door to automatically close any opening into the conveyer when said connection is fused.

9. The combination of a conveyer, and a single vertically pivoted inwardly movable door for an opening in said conveyer.

10. The combination of a gravity conveyer, and a single vertically pivoted inwardly swinging door for an opening in the conveyer.

11. In a spiral gravity conveyer, the combination with an outer shell, of an inner core, an interposed spiral blade, one or more landings, and a single vertically pivoted inwardly swinging door for an opening in the conveyer at or near a landing.

12. In a spiral gravity conveyer, the combination with an outer shell and an inner core of an interposed spiral blade, and an inwardly swinging door above the spiral and

conforming substantially to the inclination thereof.

13. In a spiral gravity conveyer, the combination with an outer shell and an inner core, 5 of an interposed spiral blade, and an inwardly swinging door for an opening in the conveyer conforming substantially to the inclination of the spiral blade, said door being hinged to the conveyer at the side of the opening of higher elevation.

14. The combination with a spiral gravity conveyer comprising an outer shell and a spiral blade, of an inwardly swinging door for an opening in the outer shell, said door and opening conforming to the inclination of the blade, and a stop for said door to permit the interior surface of the same to be flush with the interior surface of the conveyer when said door is closed.

15. In a spiral gravity conveyer, the combination with an inner core, an outer shell and an interposed spiral blade, of an inwardly swinging door for an opening in the outer shell, said door being hinged at the side of the opening of higher elevation and conforming to the inclination of the blade, and a stop device to limit the movement of the door toward the outside of the conveyer and cause the inner surface of the door to be substantially flush with the interior surface of the outer shell when said door is closed.

In testimony whereof, I have signed my name to this specification in the presence of two subscribing witnesses.

MARTIN C. SCHWAB.
